US00D847201S

(12) **United States Design Patent** (10) **Patent No.:** **US D847,201 S**
Thiel et al. (45) **Date of Patent:** **** Apr. 30, 2019**

(54) **DISPLAY SCREEN OR PORTION
THEREFOR WITH GRAPHICAL USER
INTERFACE**

(71) Applicant: **Altisource S.à r.l.**, Luxembourg (LU)

(72) Inventors: **Will Thiel**, Boston, MA (US); **Francois Silvain**, Boston, MA (US); **Tatiana Thomas**, Boston, MA (US)

(73) Assignee: **Altisource S.à r.l.**, Luxembourg (LU)

(**) Term: **15 Years**

(21) Appl. No.: **29/655,406**

(22) Filed: **Jul. 3, 2018**

Related U.S. Application Data

(60) Division of application No. 29/586,196, filed on Dec. 1, 2016, now Pat. No. Des. 826,257, which is a continuation of application No. 15/252,765, filed on Aug. 31, 2016.

(57) **CLAIM**

The ornamental design for a display screen or portion thereof with graphical user interface, as shown and described.

DESCRIPTION

FIG. 1 is a front view of a display screen or portion thereof with graphical user interface showing a first embodiment of our new design; and,

FIG. 2 is a front view of a display screen or portion thereof with graphical user interface showing a second embodiment of our new design.

The broken lines showing the display screen or portion thereof with graphical user interface is provided for the purpose of illustrating environmental structure and forms no part of the claimed design.

1 Claim, 2 Drawing Sheets
